Charles F. Markham

UNITED STATES PATENT OFFICE.

CHARLES F. MARKHAM, OF PROVIDENCE, RHODE ISLAND.

PIN.

No. 873,765.

Specification of Letters Patent.

Patented Dec. 17, 1907.

Application filed January 28, 1907. Serial No. 354,389.

To all whom it may concern:

Be it known that I, CHARLES F. MARKHAM, a citizen of the United States, residing at the city of Providence, in the county of Providence and State of Rhode Island, have invented a certain new and useful Improvement in Pins, of which the following is a specification, reference being had therein to the accompanying drawing.

10 This invention relates to improvements in the manufacture of pins such as are used principally for ornamental wear and the primary object of the invention is to provide said pin with an integral catch piece and 15 joint-ears that are formed heavier or made thicker than the body of the pin to strengthen the same.

In the construction of pins from high grade 20 or expensive material, such as solid gold, silver, heavy rolled plate stock or the like, the body portion may be made very light or thin and still, owing to its cupped shape form, be sufficiently strong and durable for all practical purposes. When a cuff pin is constructed of such thin stock it has heretofore 25 been found necessary to form the joint-ears and catch piece separately and of heavier stock and to solder the same to the body, as when they were made all in one piece with 30 the body portion, they were so thin and light that they were unsubstantial and not practical, being easily broken off and the pin destroyed.

When it was desired to make the ears and 35 tongue integral with the body in a practical manner the stock of the body had to be much thicker than was necessary in order to get the ears of sufficient strength to stand the strains, thus unnecessarily increasing the cost 40 of the pin.

My improved cuff pin is constructed to obviate the above difficulties rendering it possible and practicable to form a pin body extremely thin and light and at the same time 45 provide said body with joint-ears and catch pieces formed integral therewith, and yet of sufficient strength and stiffness to easily withstand the strains required of them.

50 My invention is fully set forth in this specification and more particularly pointed out in the appended claims.

In the accompanying drawings: Figure 1— is an enlarged view of a completed pin showing the same constructed in my improved 55 manner and the pin tongue in position in the joint and catch. Fig. 2—represents a flat

piece of stock which has been rolled, stamped or otherwise swaged to the desired thickness showing the joint-ears and catch raised or thickened on the surface of the plate, the 60 outline of the pin body being shown in dotted lines. Fig. 3—shows the pin blank cut from the sheet stock. Fig. 4—is an enlarged section on line 4—4 of Fig. 2 illustrating the thickened or reinforced ears, the center portion 65 between the ears representing the thickness of the body of the pin. Fig. 5—is a section on line 5—5 of Fig. 2 the raised portions at either end representing the thickened tongue and joint-ear, the balance of the 70 stock representing the comparative thickness of the body of the pin. Fig. 6—shows a blank form of fulcrum plate adapted to fit between and around the raised portions of 75 the ears within the body of the pin. Fig. 7 is a perspective view of the fulcrum plate 80 bent into proper form to be applied to the pin body. Fig. 8—represents one of the pins in section showing a reinforced catch or joint-ear also the fulcrum plate in position 85 in the pin. Fig. 9—is an enlarged section on line 9—9 of Fig. 8 showing the thickened joint-ears, as compared to the thin shell. Fig. 10—is a section similar to that of Fig. 9 showing the fulcrum plate as held in position 90 between the ears by setting said ears inward to grip or bind said plate and hold it in position. Fig. 11—shows a pair of rolls with recesses in the face of one, for forming thickened portions on the stock as 95 it is passed therethrough.

Referring to the drawings at 1 is the body portion of the pin which is constructed of sheet metal, said metal being rolled, swaged or stamped to the desired thickness. In constructing this pin of solid gold or silver or of a heavy roll plate stock it is desirable, on account of the expense of the stock as well as the ease with which the same is worked, to form the body of the pin as thin 100 as possible and the catch member 2 and ears 3—3 integral with the body portion, but when these pieces were formed from thin stock, and of the same thickness as the body portion, it was found that they were not practical as the ears and catch piece were not strong enough to withstand the hard usage 105 they were obliged to receive. To obviate this serious difficulty I have reinforced the said ears and catch member making them 110 thicker and stronger by drawing them up or swaging them, which may be done at the

same time the stock for the body portion is being reduced to the required thickness, if desired. One way of forming these thickened portions is to provide a pair of suitable 5 rolls for rolling the stock, one roll being arranged with indentations or recesses of the desired form or shape set at proper intervals in its face, so that the stock will be drawn, forced or swaged up into said recesses there- 10 by raising or thickening the same at the points which are subsequently formed into joint-ears and catches. I do not confine myself, however, to the production of these raised portions by the rolling of the stock as 15 the same result may be obtained by stamping, swaging or by any other means without departing from the spirit and scope of my invention. In forming these ears and the catch portion the stock is preferably raised or 20 thickened on the inner side at 4—4 of the body 1 which thickened portion is carried well down into the body portion at 5—5 there- by providing a substantial reinforcement 25 at the points which are called upon to withstand the most strain. By thickening the stock on the inner face of the ears and catch, the outside surface of the same remains smooth and regular, and even with the outer face of the body portion. A fulcrum plate 30 6 is preferably stamped out of sheet metal recessed at 7—7 to fit over the raised portions 4 of the ears and between said ears when they are turned down into the position to receive the pin tongue. Any suitable 35 bearing for this fulcrum plate may be arranged but I have shown the ends 8—8 of the plate as bent over to rest against the bottom or inner surface of the body of the pin.

40 As illustrated in Fig. 10 the ears 3—3 may be carried inward so as to better grip, bind and retain the said fulcrum plate firmly in position. The pin tongue may be placed in position in the usual way and the pin is 45 ready for service.

From the foregoing it will be readily perceived that I have produced a pin the body portion of which may be made of thin material, whereby the same may be readily 50 shaped, embossed, or otherwise worked, thereby insuring a saving in the cost of manufacture and at the same time presenting a neat and finished appearance. It will be further observed that by thickening the 55 metal to reinforce the joint ears and catch I

avoid the expense and save the time incident to the soldering of separate joint ears and catches, or reinforcing pieces, and yet produce a durable and inexpensive pin.

Having thus described my invention, what 60 I claim as new and desire to secure by Letters Patent, is:

1. An article of manufacture comprising a pin formed of sheet metal shaped to the desired form and provided with integral catch 65 and joint ears which are of greater thickness than the body portion of said pin.

2. An article of manufacture comprising a pin formed of sheet metal shaped to the desired form and provided with an integral 70 catch which is of greater thickness than the body of said pin.

3. An article of manufacture comprising a pin formed of sheet metal shaped to the desired form and provided with integral joint 75 ears which are of greater thickness than the body portion of said pin.

4. An article of manufacture comprising a pin formed of sheet metal shaped to the desired form and provided with integral catch 80 and joint ears, said catch member and ears being thicker than the body of the pin, the thickened portions extending well down into said body.

5. An article of manufacture comprising a 85 pin formed of sheet metal shaped to the desired form and provided with integral catch and joint ears which are of greater thickness than the body of said pin, and a fulcrum member notched to engage the thickened 90 portions of said joint ears, the latter being bent to retain said fulcrum member in position.

6. An article of manufacture comprising a pin formed of sheet metal shaped to the de- 95 sired form and provided with integral catch and joint ears which are of greater thickness than the body of said pin, and a fulcrum member having projections which straddle the thickened portions of said joint ears, said 100 projections being bent over to rest against the body portion of the pin, said ears being bent inward to retain said fulcrum member in position.

In testimony whereof I affix my signature 105 in presence of two witnesses.

CHARLES F. MARKHAM.
